UNITED STATES PATENT OFFICE

DEWALD STOECKER, OF ABERDEEN, SOUTH DAKOTA

NONLEAK ACCORDION PAD

Application filed January 18, 1932. Serial No. 587,414.

My present invention relates to musical instruments having rows of reeds for the production of musical notes and more particularly to accordions. The primary object 5 of the invention is to provide accordions or other musical instruments of that class with simple means that will render the instrument proof against air leaks.

To the attainment of the foregoing the invention consists in the improvement herein-after described and definitely claimed.

In the drawings:

Figure 1 is a horizontal section through a sufficient portion of an accordion to illustrate 15 the application of my improvement.

Figure 2 is a vertical sectional view approximately on the line 2—2 of Figure 1.

Figure 3 is a plan view of a portion of a 20 pad that renders the instrument leak-proof.

Before proceeding with a detailed description of the improvement it is believed necessary to state that there is arranged between the reed blocks in both the treble and bass sides of an accordion or like instrument a 25 pad which comprises a thin layer of felt, the same having openings therethrough corresponding to the wind cells in the reed blocks.

As the instrument is subjected to vibration this pad, which is expansible only a slight 30 degree, becomes hardened or does not expand sufficiently to afford a tight contact between the reed blocks and the metal or wooden plate with which the reed blocks abut, which affords air spaces or passages between the

35 reed blocks and the said metal or wooden plate of the instrument, with the result that there is a leakage of air which prevents the proper playing of the instrument so that the instrument must be repaired before the same

40 can again be raised. This air leakage is a frequent occurrence, especially in accordion instruments and, as previously stated, it is the object of this invention to prevent such leakage. This I accomplish in a very simple 45 but thoroughly efficient manner.

Only one side of the accordion is illustrated by the drawings and the type of instrument illustrated has its main body part 1 provided with a piano keyboard, having white keys 2 and black keys 3. These keys are suitably

pivoted and have their inner ends passing through the front reticulated and fabric lined plate 4 of the instrument. The keys are connected by rods 5 to valves 6, the said valves normally closing the upper and lower series of air holes 7 in a metal plate or board 8 that is arranged in the instrument and connected to the sides, top and bottom thereof. Normally the inner face of the plate 8 is covered by a thin layer of felt having holes therethrough corresponding with the holes 7. It is against this thin layer of felt that the reed blocks 9 abut, the wind cells for the reeds in the blocks being disposed opposite the respective holes 7 and the holds in the felt plate. Obviously to produce desired tones the shapes of the holes vary.

One of the inner sides of the instrument base is provided with a cleat 10, the opposite side being provided with blocks 11 and one of the ends of each of the reed blocks is projected, as at 12, and is designed to be inserted between the side and the cleat for holding the reed blocks against the pad while the blocks have screwed therein angle bolts 13 whose outer ends contact with the reed blocks for holding the same in proper contact with the pad.

In the ordinary construction of accordions or like instruments, means other than those just described may be employed for holding the reed blocks against the felt pad but it will be obvious that because of the vibration to which the reed blocks are subjected in the playing of the instrument an effective airtight joint between the said blocks and the felt pad on the plate 8 cannot be maintained. From practice I have found that it is absolutely necessary that in order to prevent air leakage in this type of instrument that a pad which embodies elasticity so that the same will yield or expand to afford an airtight joint between the plate 8 and the reed blocks 9 must be produced and such pad may be employed in conjunction with the regular thin felt pad or independent thereof. Such pad I provide and the same is indicated in the drawings by the numeral 14. The pad may be adhesively connected to the inner face of the plate 8, and the said pad is thick in com-

parison to the felt pad which is usually employed. The pad is provided with holes 15 that correspond in number with the air holes in the plate 8 and likewise with the air cells in the several reed chambers. The pad 14 is of soft material as well as embodying a comparatively large amount of elasticity. An accordion or like musical instrument employing reeds, by the employment of a simple 10 and cheaply constructed pad as above described is rendered positively air leak-proof, regardless of the vibration to which the instrument is subjected and it is thought that when the foregoing description has been read 15 in connection with the accompanying drawings the simplicity of my improved accordion construction and the advantages derived by the employment of my pad will be understood and appreciated by those skilled in the art to which the invention relates so that further detailed description will not be required. It may be necessary to state that the keys are 20 operated in the usual manner and that the bellows is attached to the reed and open end 25 of the section 1 of the accordion and, of course, the second section of the accordion is also attached to the bellows.

Any accordion or like instrument having 30 reed blocks that are not constructed of very hardest wood or layers of wood or panel work are susceptible to warping in different directions, mostly away from the plate 8. This plate 8, if not built of the hardest material 35 will warp away from the reed block 9 to assume a wavy shape. This is not absolutely true in an instrument that is provided with a metal or aluminum plate 8, but the reed block 9 is susceptible to warping or yielding from such plate, and by the employment of 40 the rubber sponge or elastic pad 14, which is set between these two bodies and is compressed in a manner as above described the spaces left by warping will be taken up by the pad, so that the instrument is rendered 45 air tight. With old instruments that are rendered defective for these reasons the employment of my pad will restore such instruments by rendering the same airtight so that old instruments provided with the improvement 50 are restored to their original construction.

Having described the invention, I claim:

An accordion or like instrument having 55 reed blocks, a plate in the instrument having holes therethrough disposed opposite the air cells in the reed blocks, valves for closing the 60 holes and keys for operating the valves, a comparatively thick soft compressible and elastic pad between the plate and the reed blocks and having openings alining with the 65 openings in the plate, said reed blocks having one of their inner ends extended, a cleat on one side of the instrument to be contacted by said extension, blocks on the opposite sides of the extension, angle bolts screwed in said

blocks and having their outer angle ends normally contacting with the reed blocks for holding the reed blocks in position and in tight engagement with the pad.

In testimony whereof I affix my signature. 70
DEWALD STOECKER.
